UNITED STATES PATENT OFFICE.

JOHN B. MORGAN, OF PHILADELPHIA, PENNSYLVANIA.

DESIGN FOR WOVEN FABRIC.

SPECIFICATION forming part of Design No. 23,840, dated December 4, 1894.

Application filed October 29, 1894. Serial No. 527,360. Term of patent 7 years.

To all whom it may concern:

Be it known that I, JOHN B. MORGAN, a citizen of the United States, residing in Philadelphia, Pennsylvania, have invented a certain 5 Design for Ticking and other Woven Fabrics, of which the following is a specification.

My design for ticking or other woven fabric is fully illustrated in the accompanying drawing, the figure of which represents two 10 complete sets of stripes.

The essential features of the design are the two wide stripes one having a plain ground with two narrow stripes at the center and the other having two narrow light stripes near 15 each side.

A is one of the main stripes having a plain back ground *a* and two well defined light stripes *a'* at the center. B is the other main stripe having the back ground *b*, preferably

of the same tint as the back ground *a* of the 20 stripe A and having a series of stripes *b'* throughout its width. The two stripes at each side are bordered by well defined narrow dark stripes *b²*.

The main stripes A and B are separated by 25 light stripes *c* giving the effect clearly illustrated in the accompanying drawing.

I

The design for ticking or other woven fabric as herein described and shown in the accompanying drawing.

In testimony whereof I have signed my name to this specification in the presence of two subscribing witnesses.

JOHN B. MORGAN..
